SASH BALANCE

Filed Oct. 27, 1947

UNITED STATES PATENT OFFICE

2,603,828

SASH BALANCE

Henry Randel Dickinson III, Grand Rapids, Mich., assignor to Grand Rapids Hardware Company, Grand Rapids, Mich., a corporation of Michigan

Application October 27, 1947, Serial No. 782,445

7 Claims. (Cl. 16—197)

1

This invention relates to improvements in sash balances.

The main objects of this invention are:

First, to provide an improved sash balance which may be quickly mounted upon a window sash, the supporting brackets constituting reinforcing elements for the frame of the sash.

Second, to provide an improved sash balance structure including a rotating tubular member having a spiral track with supporting means greatly facilitating the mounting of the balance upon a sash while permitting adjustment.

Third, to provide an improved mounting bracket for sash balances.

Further objects relating to details and economies of the invention will appear from the description to follow. The invention is defined and pointed out in the claims.

A preferred embodiment of the invention is illustrated in the accompanying drawings, in which:

Fig. 1 is a fragmentary view partially broken away and in vertical section illustrating the balance of my invention operatively associated with a window sash and its frame.

Fig. 2 is an enlarged fragmentary view in section on line 2—2 in Fig. 1.

Fig. 3 is a plan view of a blank from which one of the brackets of my invention is formed.

Fig. 4 is a fragmentary top view of a sash on which the balance is mounted.

Fig. 5 is a fragmentary view in section corresponding to line 5—5 of Fig. 1 showing the structure of the second bracket.

Referring to the drawing, the reference numeral 1 designates a window frame or casing in which a sash designated by the numeral 2 is mounted. The sash 2 comprises an upright or riser side member 3, top member 4 and bottom member 5, the side member 3 being provided with mortises 6 at its ends receiving tongues 7 on the top and bottom members.

This is a conventional sash structure but is described in view of the coacting features of the brackets of my invention. The sash is provided with a groove 8 in one edge adapted to receive the sash balance. The sash balance comprises a tubular element 9 having a spiral groove 10 constituting a track which is engaged by the follower lug 11 of the torsion member 13. This torsion member slidably embraces the tubular member and is provided with a mounting arm 14, secured to the casing by means of the screw 15. At its lower end the tubular member 9 is provided with a bushing 18 secured thereto as by the screw 19. The lower bushing is provided

with ratchet teeth 20 at its inner end. The tension rod 21 is rotatably supported in the lower bushing and provided with a ratchet head coacting with the teeth. The lower end of the coil spring 23 arranged within the tubular element is in clutching engagement with the inner end of the tension rod. The upper end of the spring is in clutching engagement with the inner end of the anchoring rod 24, which is arranged through the bushing 16 and constitutes a journal for the tubular member.

The anchoring rod or journal member 24 is provided with a flattened eye 25 receiving the pivot pin 26 passed through the ears 27 of the bracket 28. This bracket 28 is formed as a sheet metal stamping, the ears being turned downwardly therefrom, the bracket comprising a head portion 29 and a tapered prong 30 adapted to be driven into the sash dowel. This prong is of considerable length and of considerable width at its base and has outwardly facing teeth 31 on its edges. A reinforcing rib 32 is struck up on the prong to extend inwardly from the head, reinforcing the prong at the point where it is subject to bending stress particularly while being driven. The ears 27 constitute stops limiting the driving of the prong into the sash. The bottom bracket 33 is the same as that described with the exception that instead of forming the head portion 34 of the bracket with ears it is provided with a bearing opening 35 receiving the end of the bushing 18 which projects slightly from the tubular member, as shown in Fig. 1, the outer end of the tension rod is slotted at 36 to receive an adjusting tool for tensioning the spring.

It will be noted that the prongs of the brackets are driven into the tongues 7 of the top and bottom sash members and that the edges of the prongs engage the side edges of the mortises as indicated in Fig. 4. The prongs thus serve to anchor the tongues so they cannot pull out of the mortises.

The brackets enable very rapid mounting of the balance on the window sash as it is only necessary to drive them into the sash.

The upper bracket may be driven into position, thereby swingably supporting the balance, the lower bracket may then be engaged with the bearing portion at the other end of the tubular member and accurately positioned and driven into the sash.

I have illustrated and described my invention in a highly practical embodiment thereof. I have not attempted to illustrate or describe other adaptations or embodiments which I contemplate, as I believe this disclosure will enable those

skilled in the art to embody or adapt my invention as may be desired.

Having thus described my invention, what I claim as new and desire to secure by Letters Patent, is:

1. In a sash balance the combination with a sash comprising a side member having mortised ends, and top and bottom members having tongues disposed in the mortises, of a rotatable elongated member having a spiral track, a journal member for one end of said rotatable elongated member and top and bottom attaching brackets comprising heads and integral tapered blade like prong portions with the planes of the prong portions disposed substantially at right angles to the lengths of the rotatable elongated member and sash side member, the prongs being provided with outwardly facing teeth on their side edges, the prongs being driven into the sash interlockingly engaged the tongues of the top and bottom sash members, and the sides of the mortises receiving the same, the head of the upper bracket having downturned ears disposed parallel to said rotatable elongated member and constituting sash engaging stops, the end of the journal member being disposed between and pivotally connected to said ears, said ears and the pivotal connection of the journal member thereto retaining said journal member against axial rotation, whereby the assembly is swingably mounted on the upper bracket, the prongs of the brackets having longitudinal ribs extending from the heads thereof, the head of the lower bracket being provided with a bearing opening for the lower end of the rotatable elongated member, and a torsion member coacting with said track.

2. In a sash balance the combination with a sash comprising a side member having mortised ends, and top and bottom members having tongues disposed in the mortises, of a rotatable elongated member having a spiral track, a journal member for one end of said rotatable elongated member and attaching brackets comprising heads and integral tapered blade like prong portions having toothed edges, the blade-like prong portions being disposed with the planes thereof substantially at right angles to the lengths of said rotatable elongated member, the prongs being driven into the sash interlockingly engaging the tongues of the top and bottom sash members, and the sides of the mortises receiving the same, the journal member being non-rotatably connected to one bracket, the other bracket being provided with a bearing opening for the other end of the rotatable elongated member, the prongs of the brackets being disposed to be driven into the tongues of the sash members when the brackets are in assembled relation to the anchoring rod and tubular member.

3. In a sash balance the combination of a rotatable elongated member having a spiral track, a journal member for one end of said rotatable elongated member and attaching brackets comprising head and integral tapered blade like prong portions having toothed edges, the blade-like prong portions being disposed with the planes thereof substantially at right angles to the lengths of said rotatable elongated member, the journal member being non-rotatably connected to one bracket, the other bracket being provided with a bearing opening for the other end of the rotatable elongated member, the prongs of the brackets being disposed to be driven into a sash when the brackets are in assembled

relation to the anchoring rod and tubular member.

4. A sash balance including a tubular element having a spiral track, a torsion member coacting with said track, a journal member for one end of said tubular element, a coiled spring arranged within said tubular element and connected thereto at one end and to said journal member at its other end, and mounting brackets for said tubular element, one bracket having ears projecting therefrom in the direction of the length of the tubular element, said journal member having one end thereof disposed between and pivotally connected to said ears for lateral swinging movement of the tubular element, said ears and the pivotal connection of the journal member thereto retaining said journal member against axial rotation, the other constituting a bearing for rotatably supporting the other end of the tubular member, said brackets having integral pointed blade like toothed prongs of substantial length and width adapted to be driven into the part on which the tubular element is mounted.

5. A sash balance, comprising a tubular element having a spiral track and a coacting torsion member, a journal member at one end of said tubular member, and mounting brackets for said tubular member, said journal member being non-rotatably engaged with one bracket, the other end of the tubular member being rotatably supported by the other bracket, said brackets comprising head members and pointed blade-like driving prongs of substantial width and length adapted to be driven into the part in which the tubular element is mounted and having serrated edges, the blade-like prongs being disposed with the planes thereof substantially at right angles to the length of the tubular element.

6. An attaching bracket for a sash balance formed of sheet metal and comprising integral head and drive prong portions, said portions being flat and disposed generally in a common plane, the prong portion being tapered and having serrated edges, the head having an opening therein for receiving a part of the balance to be supported, there being a reinforcing rib extending across the merging zone of the head and prong, said rib being struck from the body of the bracket.

7. An attaching bracket for a sash balance formed of sheet metal and comprising a head portion and a blade-like prong portion integral with said head portion, said head and prong portions being disposed generally in a common plane, the prong portion being tapered and having serrated edges and constituting means to be driven into a sash, the head portion having a pair of spaced ears integral therewith and projecting therefrom at substantially right angles to the general plane of the bracket, said ears having aligned openings for receiving a pivot pin for pivotally supporting a part of a sash balance, said ears constituting sash engaging stops.
